UNITED STATES PATENT OFFICE.

WESLEY E. COCHRAN, OF CLEVELAND, OHIO.

DESIGN FOR A COMBINATION LAMP AND LICENSE-PLATE HOLDER.

Application filed November 13, 1922. Serial No. 4,273. Term of patent 3½ years.

To all whom it may concern:

Be it known that I, WESLEY E. COCHRAN, a citizen of the United States, residing at Cleveland, in the county of Cuyahoga and State of Ohio, have invented a new, original, and ornamental Design for a Combination Lamp and License-Plate Holder, of which the following is a specification, reference being had to the accompanying drawings, forming a part hereof.

Figure 1 is a face view of the combination lamp and license plate holder.

Fig. 2, an edge view or side elevation of the same.

I claim:—

The ornamental design for a combination lamp and license plate holder, as shown.

WESLEY E. COCHRAN.
